UNITED STATES PATENT OFFICE.

PAUL R. COLLIER, OF PHILADELPHIA, PENNSYLVANIA.

DESIGN FOR A HEADLIGHT.

57,890.

Specification for Design.

Patented May 17, 1921.

Application filed October 19, 1920. Serial No. 418,108. Term of patent 7 years.

To all whom it may concern:

Be it known that PAUL R. COLLIER, a citizen of the United States, residing at Philadelphia, in the county of Philadelphia, State of Pennsylvania, have invented a new, original, and ornamental Design for Headlights for Automobiles or other Vehicles, of which the following is a specification, reference being had to the accompanying drawing, forming part thereof.

Figure 1 is a perspective view of a headlight showing my new design.

Fig. 2 is a front elevation thereof.

Fig. 3 is a side elevation thereof.

I claim:

The ornamental design for a headlight as shown.

PAUL R. COLLIER.
